UNITED STATES PATENT OFFICE.

BERT L. HUTTON, OF CHICAGO, ILLINOIS, ASSIGNOR OF ONE-HALF TO AUGUST W. FETT, OF CHICAGO, ILLINOIS.

DESIGN FOR A PHOTO-FRAME.

45,260.

Specification for Design.

Patented Feb. 17, 1914.

Application filed October 31, 1913. Serial No. 798,596. Term of patent 3½ years.

To all whom it may concern:

Be it known that I, BERT L. HUTTON, a citizen of the United States, residing at Chicago, in the county of Cook and State of Illinois, have invented a new, original, and ornamental Design for a Photo-Frame, of which the following is a specification, reference being had to the accompanying drawing, forming part thereof, and wherein the figure is a plan view of the photo-frame, illustrating my new design.

I claim:

The ornamental design for a photo frame,
as shown.
Chicago, Illinois, October 22, 1913.

BERT L. HUTTON.
